WIRE FORMING MACHINE

Mauritz Olson, Bridgeport, and Richard A. Johnson, Fairfield, Conn., assignors to The A. H. Nilson Machine Company, Bridgeport, Conn., a corporation of Connecticut

Application December 5, 1935, Serial No. 52,992

18 Claims. (Cl. 140—71)

This invention relates to wire feeding and forming machines of the slide type and is particularly adapted for the formation of comparatively large articles requiring long lengths of wire such as, for instance, garment hangers, bucket bails, frames for strainers, etc.

The formation of these different articles on this machine would obviously require a change of tools whereas the several cam shafts, the feed mechanism, wire guides and some of the bending tools would remain very much as are herein shown.

The present machine has, therefore, been designed with a view of adapting it not alone for the formation of coat hangers but as a general purpose slide machine for forming wire into special shapes thus making of it a more attractive manufacturing proposition and whereby machines for these specific purposes will not each have to be entirely especially built.

One of the objections heretofore experienced in wire forming machines particularly where long lengths of wire are fed from a reel, is the difficulty of feeding proper and uniform lengths of wire from which to form the specific articles to be formed. This apparently is due to the type of feed mechanisms employed and the means for operating the same more particularly the stopping and starting of the feeding means. Where feed rollers are employed and operated from a drive means and where they are started and stopped by brake mechanisms applied to the rollers, or other means employed to check the effect of the power drive, the stopping of the feed, is quick, presumably with the forward end of the wire in engagement with a stop, in which case the feed is likely to be started with a jerk depending upon the quickness of the releasement of the brake or other means of retarding the movement of the feed, so that the feeds as a whole, as we have observed them, are not as desirable as the form herein employed whereby a gradual starting and stopping of the feeding movement is assured and whereby uniform lengths of wire are fed and positioned for cutting.

Another objection experienced with certain types of machines feeding long wires, is that the forming mechanism remains idle from the time the wire is completely formed until the feeding wire is fed the full length thereby tripping a clutch and setting the forming mechanism in motion.

In accordance with the construction of this machine, the wire which is taken from a reel is

fed into the machine in a horizontal plane and cut to uniform lengths, which constitutes the first operation. It is then shifted to a lower level where a hook is formed upon the forward end of the wire, and during which time a second length of wire is fed into the machine and cut off. After the hook has been formed on the end of the first wire blank it is again shifted to a third and lower level where it is bent to form the shoulder and shank portions and the latter twisted to complete the hanger. The machine thus operates upon three wire blanks simultaneously on different levels and produces a complete coat hanger with each cycle of the machine. By this means the speed of production is increased since the time actually consumed in the production of a hanger is only that of the time required for the performance of the longest operation, namely that of the bending of the hook.

The machine includes a novel form of feed mechanism whereby the wire is taken from a reel and fed into position in the machine preparatory to being cut off in suitable lengths. This feed obviously operates automatically and is of such a nature as to provide a feed which insures a slow preliminary feed, a rapid feed of the intermediate portion of the wire blank and a slow final movement preparatory to cutting. In this respect the forward end of the wire is fed against a stop at the same instant the said rolls cease to rotate only long enough to permit of the cutting operation and the shifting of the wire from its feeding plane to a lower plane where the hook is formed upon one end.

The wire is fed into a relatively long guide way which is made separable along a vertical and horizontal plane and adapted to be periodically opened for the shifting of the wire blank to the intermediate level where it is retained during the formation of the hook which is produced by suitable forming dies that are slidably operated, no rotary members being used in this hook forming operation.

The hook being formed, it is promptly moved to a lower level where a pair of hook-ended slides are employed for folding the wire around a stationary former in a way to bring the hook and the straight end together in parallel relation and in which position they are grasped by a rotatable head that winds the two wire shank portions around each other intermediate of the formed body portion of the hanger and the hook in a way to form a twisted shank for the hanger.

The invention further consists in the novel construction, combination and arrangement of

parts as hereinafter more fully described, and as illustrated in the accompanying drawings forming a part of this specification and wherein is shown an embodiment of the invention. It is to be understood however, that the description and drawings are to be considered as illustrative and that the invention is intended to be limited only by the scope of the claims hereby appended.

In the accompanying drawings in which like characters of reference are employed to designate like or corresponding parts throughout the several views,

Fig. 1 shows a top plan view of my improved wire forming machine including the feed mechanism.

Fig. 2 is also a top plan view, upon an enlarged scale, of the central portion of the bed of the machine, showing in a general way the tools for performing the several operations upon the wire.

Fig. 3 shows an enlarged longitudinal sectional elevation, taken on line 3—3 of Fig. 2, and drawn on the same scale.

Fig. 4 is an enlarged front view of the wire cutter shown in Figs. 3 and 5.

Fig. 5 is a vertical longitudinal section through the wire cutter taken on wire line 5—5 in Fig. 4.

Fig. 6 is an enlarged plan view of the hook forming mechanism.

Fig. 7 is a vertical cross section of the hook forming mechanism shown in Fig. 6 and taken on line 7—7.

Fig. 8 is a further plan view similar to Fig. 6 except that the movable wire guide bar and forming tools are in an open position.

Fig. 9 is a vertical cross section taken on line 9—9 of Fig. 8.

Fig. 10 is a vertical sectional view on an enlarged scale through one pair of feed rolls and associated operating mechanism shown at the right in Fig. 1, and taken on line 10—10 of Fig. 11.

Fig. 11 is a sectional elevation of the feed mechanism taken on line 11—11 of Fig. 10.

Fig. 12 is a vertical longitudinal section taken on line 12—12 of Fig. 2 with tools in position preparatory to twisting the shank.

Fig. 13 shows a detail to be read in connection with Fig. 12 shewing the combined wire guide and stripper in raised position.

Fig. 14 is an enlarged detached side view of the hanger 93 and its notched lowering tool, and the associated guide bars and former, and taken on line 14—14 of Fig. 2 and shown in Fig. 12, employed to shift the wires from upper to lower levels.

Fig. 15 is a detail plan of guide bars and former, and hook forming tools in closed position, the wire blank being indicated in dotted lines.

Fig. 16 shows a further detail plan view of the former and a wire blank in an advanced stage of formation and the forming tools positioned in relation thereto.

Fig. 17 shows a further advanced position of the wire forming tools and wire blank, and

Fig. 18 shows a further detail view somewhat like the preceding ones again illustrating an advanced step in the formation of the wire coat hanger preparatory to twisting as shown in Fig. 2.

As previously suggested, this wire forming machine is designed principally as a slide machine since all forming tools are operated through slides and cams. The principal forming tools operate on horizontal lines except that of the twisting head which in addition to having a horizontal

sliding movement, has a rotary movement whereby the twisting of the shank portion of the hanger is accomplished. The machine is designed to continuously operate in a way to produce complete garment hangers automatically and discharge them from the machine at the rate of approximately forty a minute.

Referring first to the characters of reference marked upon the drawings, as clearly appears in Fig. 1, 20 represents the bed which in design has a comparatively flat top surface and is supported upon suitable legs 21 which, however, for the most part have been omitted to save space. 22 represents a main shaft that is hung in bearings 23 secured to the main bed and is provided with a belt wheel 24 which may be connected to be driven by a motor, not shown, and a fly wheel 25 at the opposite end. A clutch 26 is also provided upon this shaft for engagement with the continuously driven belt wheel, said clutch being operated through a hand lever 27 pivotally connected to a fixed bearing of the machine and is connected by a rod and lever 28 with said clutch for its operation. Power is transmitted from the shaft 22 through a pinion 29 at a reduced ratio to the larger gear 30 on a cam shaft 31 that is journaled in bearings 32—32 of the bed. This cam shaft is connected to drive two additional cam shafts 33 and 34 arranged at right angles thereto, the first mentioned being connected through bevel gears 35 and the last mentioned through similar bevel gears 36 whereby the three said shafts are driven continuously along with the main driving shaft 22 when the clutch 26 is engaged. Shafts 31, 33 and 34 are all provided with cams for operating various slides, levers and forming tools of the machine and in addition the shaft 33 serves to operate a wire feed mechanism shown in Figs. 1, 10 and 11 which, due to its rapid successful operation, materially adds to the uniform and successful production of commercially perfect garment hangers. Since this feed mechanism forms the introduction of the wire into the machine, and thus constitutes the first or preliminary operation, it will next be described, including its operative connection with the cam shaft 33 through which it is operated. In this respect it will be noted that this shaft 33 is journaled in bearings 37—37 of the bed and carries a pinion 38 that drives a larger gear 39 mounted upon a short shaft 40, journaled in hangers 41 secured to the underside of the bed. This gear is provided, upon one side, with a series of four rollers 42, for engagement with and disengagement from radial slots 43 formed on the adjacent side face of a gear 44 that is mounted upon a short shaft 45 also journaled in the hangers 41. This last mentioned gear 44 is thus operated one-quarter turn by the gear 39, for the feeding of a length of wire, with each one-quarter turn of the gear 39 through the engagement of the rollers 42 with the slots 43 after the manner of a Geneva movement thus producing alternate quarter rotations of the gear 44 and a consequential feeding movement of the wire with each rotation of the cam shafts so as to not only feed and cut off a length of wire with each cycle of the machine but to perform other operations on the advanced blanks and the resultant completion of a finished garment hanger.

There are two pairs of feed rollers, each pair including an upper roller A and a lower roller B, as clearly shown in Figs. 10 and 11, the two pairs being substantially alike in construction though operated through a common gear drive. 75

We will, therefore, first describe one pair of these feed rollers which should suffice for a proper understanding of both and then further describe the driving connections for the two pairs from the before mentioned gear 44. A suitable supporting frame 46 is provided for the feed and is secured to the bed of the machine by screws 41, see Fig. 1. A shaft 48 is journaled in the lower portion of this frame for each of the lower feed rollers B and is provided with a gear 49 upon its outer end that meshes with and drives a gear 50 secured on the outer end of an upper shaft 51 that supports the upper feed roller A. This upper shaft is journaled in a bearing block 52 that is pivotally supported at 53 and carries a spring 54 secured to its top side to exert a yieldable downward pressure upon wire *a* between the feed rollers A and B. An adjusting screw 55 is threadably mounted in a fixed plate 56 secured to the frame 46 and has its lower end in engagement with the said spring 54 in a manner to provide an adjustable yieldable tension of the rollers upon the wire to be fed. As will be seen there are two sets of these feed rollers, 25 shafts and gears so that the wire is drawn in through the straightening rollers A' from the coil, passed through the two feed rollers, under the cutting off mechanism and into guide bars 71 and 72. These two sets of feed rollers are operated from the before mentioned shaft 33 through the gears 38, 39, 44 and its short shaft 45. The gear 44 meshes with and drives a smaller gear 57 on an intermediate shaft 58 journaled in bearings on the underside of the bed, and carries a larger gear 59, see Figs. 10 and 11, that meshes with a smaller gear 60 on each of the before mentioned roller shafts 48, and whereby the gears 49 are operated and which in turn operate the upper gears and rollers.

40 Next adjacent to the feed mechanism is positioned the wire cutter which serves to cut the wire blanks from the main supply with the completion of each feeding operation. This mechanism will probably best be understood by reference to Figs. 1, 4 and 5 which, as will be seen, comprises a bracket 61 in which is adjustably mounted a quill 62 through which the wire *a* is fed. A cutter lever 63 is pivotally supported as at 64. The forward end of this lever is guided in a pocket of the bracket 61 formed in part by a plate 65 and carries a cutter 66 that is secured to the lever by a screw 67 and made adjustable with respect to the lever by an adjusting screw 68. The rear end of the lever is provided with a cam roll 69 that engages a groove in a cam 70 on shaft 31 that serves to move the rear end of the lever up and down in a way to reciprocate the before mentioned cutter 66 with respect to the wire quill in a manner to cut off wire blanks.

50 The length of wire to be used for a hanger is fed in between the edge portions of a pair of guide bars 71 and 72, the former being a stationary bar secured to the bed of the machine, see Figs. 2, 12, and 6 to 9 inclusive, by means of screws 73. The somewhat similar bar 72 is provided with a longitudinal groove 74, see Figs. 7, 9 and 14, formed in its inner edge portion to receive the wire and support it during the feeding operations and is adapted to be moved toward 55 and from the edge of the stationary bar in a way to receive the wire and release the blanks as they are cut.

55 In this connection it is to be understood that when the wires are fed into the groove 74 it also passes through the upper notch *h* in the lower-

ing tool 92 which serves to support and lower the wire when the movable bar 72 is open. This bar 72 is loosely supported upon brackets 75 and the clamping plate 76 and is thus adapted to move to and from the edge of the fixed bar 71 so as to permit the wire blank, after having been fed longitudinally therein and cut off, to be moved to a lower level preparatory to the formation of the hook on the forward end of the wire blank. This movable bar is normally held up against the fixed bar by means of springs 77 of which two are shown in the drawings. The movable bar is moved to and from the fixed bar against the resistance of these springs through links 78 whose ends are hingedly connected to the fixed and movable bars respectively.

This sliding movement of the movable bar with respect to the fixed bar is actuated through the cam 79 on the shaft 34, see Figs. 1, 2, 6 and 7, through the medium of a bell crank lever 80 which is fulcrumed on the bed and has a roller 81 upon one end to engage with the side of the said cam and has a slot and pin connection 82 with the movable bar so that with each rotation of the cam the bell crank lever is given a forward and backward movement in a manner to draw the movable bar longitudinally and sideways, being guided by the links 78, and against the action of the spring 77.

An opening 83 is formed in the bed through which the completed garment hangers are dropped from the former 84 of the machine. This former is supported by a bracket 85, see Figs. 1 and 12, in a way to overhang the opening 83 in the bed and so that when the hanger is formed it will be free to drop out when released by the tool 86. The before mentioned clamping plate 76 is attached to a block 87 which in turn is adjustably secured to a slide 88 that carries a roller 89 that operates in a path 90 of a cam 91 secured to the cam shaft 31.

In Fig. 14 the groove 74 in the movable guide bar 72 is indicated in dotted lines and the teeth in the lowering tool 92 carried by the hanger 93 in full lines. As will be seen from Figs. 1 and 2 there are four of these hangers carrying similar special shaped tools having toothed edges 94 that operate through suitable openings 95 in the movable bar and serve to support and move the wire blank from one level to another. Three of the hangers 93 are carried by a longitudinal rod 96, see Figs. 1, 3 and 12 and are provided with springs 97 that serve to normally hold the notched face of these tools 92 up against the fixed bar and former yet are free to move vertically to engage the incoming and successive wire blanks. The rod 96 is carried by two arms 98-99 and an intermediate arm 99 which arms in turn are secured to a rocker shaft 100 journaled in bearings 101 in the top portion of the bracket 85. This rocker shaft is in turn provided with a cam lever 102 which bears a roller 103 that engages the side portion of the before mentioned cam 91 and whereby the rocker shaft, rod 96 and the three depending hangers 93 are operated.

The fourth hanger 93 is carried on an arm 104 that is secured on shaft 100 and also serves to move the wire blank to the second or hook forming level. The arm 99 which is also mounted upon the rocker shaft 100 has a hanger 104 hingedly hung from its forward end and provided with a spring 105 that normally holds the beveled edge 106 of its tool 92 against the bevel 107 formed on the nose 108 of the former 84. The hanger is provided with a guide 109, secured

to bracket 85, which prevents sidewise movement and insures a proper alignment of the V-shaped notch 111 of the tool with the axis of the rotatable twisting head 110. This V-shaped notch 111 serves to receive and guide the free ends of the wire into alignment as the same are being folded around the former as will later be described.

The tool 111 further operates, after the wires have been so positioned and grasped by the twister, to raise out of engagement with the looped ends of the wire, and so remains in an elevated position until the twisting operation has been completed, whereupon the tool is lowered in a manner to engage the twisted shank portion c of the hanger C and strip it free of the projected forming nose 108 on the front edge of the former 84 whereby spaced apart portions d-d of the hanger, see Figs. 2 and 18, are formed.

After the wire a has been fed in between the fixed and movable guide bars 71 and 72 and the blank severed by the cutter 66, the movable guide bar is operated to free the blank whereby the tools 92, see dotted line, Fig. 12 and full lines, Fig. 14, are moved down slightly to shift the wire to the second level, see Fig. 9, and h in Fig. 14.

The hook e on the forward end of the blank is formed as soon as the blank has been lowered to its second or intermediate position. These hook forming operations are performed by three tools, first a stationary tool 112 shown in dotted lines in Figs. 6 and 8 and in cross section in Figs. 7 and 9. It is secured to the underside of a block 113 which is attached to the top of the bed by screws 114 and is cut away upon the underside to allow free outward movement of the hook end of the wire with the folding of the wire around the shoulder portions 115 of the former plate 84. 116 represents a special shaped movable tool that engages the end portion of the wire blank while the latter is in the position shown in Fig. 8 and bends said end portion into the concaved portions of the stationary tool 112 leaving the wire end free and disposed outward, see dotted lines, Fig. 6, in the path of the tool 117 which is the next to operate. The movable tool 116 is carried by a slide 118 that is mounted in ways of the bed and carries a roller 119 to engage the groove of the cam 120, see Fig. 1, mounted on the cam shaft 31. The tool 117 is carried by a slide 121 which is also mounted in the bed and carries a roller 122 which engages a groove in the cam 78. From the foregoing it will be seen that the hook is formed by the three tools as the result of two operations, the first of which shoves the blank against the fixed tool in a way to partially form the hook whereupon the second movable tool shoves the remaining free end portion of the wire around and against the back of the projected portion b of the tool 116 in a way to produce the form of hook desired. The formation of the hook having been completed, the tool 116 is drawn back until the formed hook is positioned beneath the tools 123 and 124. The next operation is to lower the wire blank to the third level and clear the forming tools for the incoming or next blank. This shifting of the wire is again accomplished in part by the notched tools 92 together with two additional tools 123 and 124 which are attached to hanger 126 and positioned to engage the wire hook when formed and adapted to strip it from the tool 116 after the tool 117 has been withdrawn.

A stop 127 is adjustably mounted in a block 128 secured to the guide bar 71 in line with the movement of the forward end of the wire blank to dependably stop it and insure proper and uniform lengths of wire as are necessary from which to form the hangers.

The hanger 93 at the left, see Figs. 1 and 3, is carried by an arm 125 secured to the before mentioned rocker shaft 108, which, as before indicated, is actuated through the arm 102 and the cam 31. A spring 130 is provided for this hanger 93 in a way to provide a tension therefore and insure proper registration of its tool 92' with and operation upon the end portion of the wire. This tool 92' has no teeth in its edge portion, 15 like the tools 92, and simply serves to act upon and lower the forward end portion of the wire. 131 represents an arm that serves to support the hanger 126 and its tools 123 and 124. This arm is free to rock upon the rocker shaft 108 and includes a rearwardly projected member 132 that carries a roller 133 that engages a path in the before mentioned cam 120.

The former 84, before referred to and clearly shown in Figs. 2 and 15 to 18 inclusive, is an 25 elongated member that is secured to the underside of the bracket 85, and includes a straight back edge portion f, see Figs. 12 and 15, against which the clamping head 76 and two of the notched tools 92 operate, and two rounded shoulder end portions 115, two similarly concaved front edge portions g-g and the before mentioned projected beveled edged nose 108, and thus constitutes the former around which the garment hanger is bent and formed and upon which it is 35 held and supported during the twisting of the shank which is formed adjacent to the hook end between it and the shoulder portion of the hanger.

After the hook has been formed and the wire lowered through the medium of the several tools 40 92 to the third or lowermost level, the opposite end portions of the wire become free for further bending operations. As before suggested, there are two of these former tools, one for each shoulder portion of the former, and serve to simultaneously bend the end portions of the wire forward and inward around the before mentioned shoulders 115 by a pair of tools 134 carried by spring and cam actuated rocker arms 135 fulcrumed as at 136 upon slides 137 that are provided with rollers 138 to engage a cam path 139 of a cam 140 in one instance and in the before mentioned gear 30 in the other. These cams obviously serve to move the arms 135 and their tools forward and backward with respect to the shoulder portion of the former.

These rocker arms 135 are provided upon their rear ends with rollers 141 that engage cam blocks 142 secured to the bed and a spring 143 is provided to normally hold these rollers against the face of the blocks so that with the engagement of the rollers with the high portion of the cams 142, the slides 137 will be moved forward and cause the bending tools to engage the end portions of the wire and bend them forward around the 65 said shoulder portions, see dotted lines Fig. 2, and dispose them in approximately the position shown in Fig. 16, the hook end of the wire passing through the then horizontally positioned opening of the twisting head.

In this connection it will be seen that a pair of guides are positioned upon opposite side portions of the top of the bed between which the ends of the wire travel during the bending operations just described. These guide members are 75

substantially alike in construction, the lower one 144 is secured directly to the bed, while the upper one 145 is also secured to the bed through the medium of brackets 146 though is arranged in spaced relation to the lower guide member so as to permit the wires to be freely moved therebetween and guided into the twisting head and the V-shaped notch 111 of the tool 86.

A second pair of wire closing tools 147 which are alike in construction and operated through similar mechanisms, see Figs. 1, 2, 3, 16 and 17, is provided to engage the wires after the same have been bent over the shoulders and disposed in approximately the position indicated in Fig. 16 for the purpose of closing the wires against the front edge portion of the former and around its nose preparatory, as shown in Fig. 18, to the twisting of the aligned shank portions of the wire.

These closing tools 147, for the most part, move horizontally to engage the wire end portions after they have been bent forward by the tools 134, to close them against the nose of the former as in Fig. 18. They are also moved vertically as well as horizontally whereby they are raised from the position shown in Fig. 3 as they recede from the closing operation, shown in Fig. 18, to a slightly higher plane in their return movement to normal position as indicated in Fig. 2 so as to be out of the way of the next incoming wire and during the operation upon that wire by the tools 134.

These closing tools are carried by arms 148, see Figs. 1, 2 and 3, which in turn are mounted to swing upon vertical posts 149 that have their bearings in the bed, are provided with collars 150 which are normally seated upon the bed in a manner to form a normal and operative position for the closure tools when in their lowered position. The posts 149 extend down through the bed and are provided with a swivel connection 151 with arms 152 and 152' that are carried upon a rocker shaft 153 journaled in hangers 154 secured to the underside of the bed. The arm 152' which like the arm 152 is secured to the rocker shaft, differs from the arm 152 in that it extends rearward and carries a roller 155 to engage a cam groove in the side of the gear 30. This line of connection obviously provides for the raising and lowering of the closing jaws 147 in the manner and for the purposes heretofore described.

The closing movements of these two jaws and their arms are alike in construction and therefore similar reference characters will be used to describe them as follows:

The forward end portions 156 of links 157 are swivelly connected to the before mentioned arms 148, while the rear ends 158 are likewise swivelly connected to the slides 159 which are reciprocably mounted in the bed and are provided with rollers 160, see Fig. 1, that engage grooves in the cams 140 and 91 respectively, on shaft 31, whereby reciprocatory movement of the slides and links are provided in a manner to swing the arms and closure tools upon the pivots 149.

As will be understood from the previous description and the illustrations, the wire end portions when brought to the position indicated in Fig. 16 are first received by the V-shaped notch 111 which brings them together, one above the other, in the pocket and opposite the vertical edge portion of the nose preparatory to the closing operation of the tools. The said notched tool is, at this time, being gradually raised and slides back on the beveled shoulder 107, see Fig. 13, as the closing tools are tightened in upon the wires,

and becomes entirely free of the wires which have now been bent into substantially the shaping shown in Fig. 18, whereupon the twisting head moves forward to grasp the wire ends. The twisting operation then follows leaving the completed hanger positioned upon the former substantially as shown in Fig. 2 whereupon the tool 86 descends in a manner to engage the blank portion of the hanger and strip it from the former.

The twisting head 110 is rotatably mounted in 10 bearings of a slide 161 in the bed and is adapted to be moved toward and from the nose of the former. The said head is adapted to receive the aligned wire ends of the hanger and to close its jaw down upon the wires whereupon rotary movement is imparted and serves to twist the shank portions of the wire around each other, after which they are released leaving the hanger free to drop out. In this connection the slide 161 mounted in the bed carries aligned bearings 162 20 that serve to rotatably support the spindle 163 of the twisting head. This spindle includes a toothed peripheral portion 164 forming a gear that is engaged and rotated by a toothed segment 165 that is hung on a short shaft 166 carried in 25 the two upstanding brackets 167 secured to the bed of the machine.

This segment 165, which has a toothed lower edge is adapted to be swung backward and forward upon its pivot 166 for the purpose of rotating the spindle 163 and its twisting head, by a cam 168 upon the shaft 34 through a lever 169 that is hingedly connected to the bed as at 170 and carries a roller 171 for engagement with the groove in the side of the cam. A link 172 connects the inner end of this lever with the intermediate portion of the segment as at 173. The slide 161 which carries bearings 162 is adapted to be moved forward and backward to bring the twisting head into and out of engagement with the wire ends by means of a bell crank 174 that is pivotally connected to the bed at 175, has its longer end 176 connected with the slide and the other end suitably connected to a cam slide 177 fitted in the bed and carrying a roller to engage 45 a groove in the cam 178 mounted on the before mentioned shaft 33.

A second bell crank lever 179 is also employed in connection with the operation of this twisting head and is pivotally connected to the bed at 180, 50 has its longer end in operative engagement with a shifting rod 181 that is slidably mounted in the aligned bearings 162 heretofore mentioned and has a forked end 182 that engages a collared sleeve 183 of the twisting head. This sleeve is 55 provided with adjustable contact screws 184 and 185 which serve to engage cam surfaces 186 and 187 on a jaw 188 that is pivotally mounted in the head on a pin 189 and serves to operate against the fixed lower jaw 190 of the twisting head so 60 that as the sleeve is shifted forward and backward through the shifting rod and its operative connections the two cam surfaces on the jaw will be alternately engaged to rock the jaw on its pin in a way to engage and release the wires.

The before mentioned bell crank 179 has its short end engaged as at 191 with a slide 192 fitted to reciprocate in the bed and held down in position by a plate 193. This slide carries a roller 194 for engagement with the groove in the cam 195 70 carried on the before mentioned shaft 34. The slide 192 includes a plate 196 having a reduced forward end positioned close adjacent to the front of the twisting head better to guide the hooked end of the wire between the jaws of the head 75

and obviously is moved back through the action of the slide after the wire ends have been aligned in the head.

The sequence of operations has been brought out in the foregoing description of the construction of the machine better to impart a clearer understanding of the construction and operation of the machine, and thus making a further description of the operation unnecessary. In this respect attention is called to the introductory paragraphs of the specification which serve to familiarize the reader with both the description of the machine and respective operations which were to follow. Among the important or outstanding features of the wire forming machine is the feeding mechanism which in practice has proven to be a superior feeding device and much more dependable than most wire feeds. Next important is the general design of the machine whereby three separate wires in different stages of formation of a coat hanger is going through the machine simultaneously thus materially increasing production, and whereby different sets of forming mechanism simultaneously operate upon different portions of the three wire blanks in a way to complete a hanger with each rotation of the main cam shaft.

Having thus described our invention what we claim and desire to secure by Letters Patent is:

1. In a wire forming machine of the class described, means for feeding wire into the machine, guide bars between which the wire is fed, means for cutting the wire off to form blanks, means for operating the guide bars to free the blanks after the same have been cut, means for moving the wire to a lower level, means for forming a hook upon one end of the blank while in the lower level, means for bending the wire around a form, and means for uniting the end portions of the wire.

2. In a wire forming machine of the class described, means for feeding wire into the machine, guide bars between which the wire is fed, means for cutting the wire off to form blanks, means for separating the guide bars to free the wire blank, means for lowering the wire blank as the bars are separated, means for forming a hook on one end portion of the wire blank, a former, means for closing the end portions of the wire around the former and bringing the ends adjacent each other, and means for twisting the end portions of the wire to unite the same.

3. In a wire forming machine of the class described, means for feeding wire into the machine, guide bars between which the wire is fed, one of said bars having a groove in its edge portion to receive and guide the wire, means for cutting the wire off to form a blank, means for lowering the wire blank from between the guide bars to a lower level, means for forming a hook upon one end of the blank while in said lower level, a former, means for bending the wire around the former in a way to bring the ends adjacent each other, and means for twisting the end portions of the wire to unite the same.

4. In a wire forming machine of the class described, means for feeding wire into the machine, means for cutting the wire to lengths, means for moving the wire blank from the feeding level to a second or hook forming level and for moving said wire a second time to a third level for final operations, means for forming a hook upon one end of the blank while in the second level, means for bending the wire upon a form and means for uniting the end portions of the wire while in the third level.

5. A wire forming machine adapted to simultaneously operate upon three separate wire blanks, including guide means between which the wire is fed, means for cutting the wire off to form lengths, means for moving the wire blank from the feeding level to a second or hook forming level and for moving the second time to a third level for final operations upon the wire, means for forming the hook upon one end of the blank, means for bending the wire around a former and means for uniting the end portions of the wire to form a garment hanger.

6. In a wire forming machine of the class described, means for feeding wire from a reel into the machine, guide means to receive the wire, means for cutting the wire to lengths, means for moving the wire to a different level, a fixed forming tool to receive one end of the wire, two slidable forming tools, means for operating the latter in relation to the fixed tool to form a hook, means for moving the wire to a lower level, a former, tools for bending the end portions of the wire around shoulder portions of the former, means to guide the end portions of the wire during their bending movements, closing tools for engaging the said bent end portions of the wire and means for connecting the end portions of the wire to form a garment hanger.

7. In a wire forming machine of the class described, including a bed, means for feeding the wire from a reel into the machine, guide means to receive the wire above the bed, means for cutting the wire to lengths, means for moving the wire to a different level, a fixed forming tool to receive the wire secured upon the bed, two additional forming tools slidably mounted on the bed, means for operating the latter in relation to the fixed tool to form a hook, means for lowering the wire, a former, tools slidably mounted on the bed for bending end portions of the wire around the shoulder portions of the former, means to guide the end portions of the wire during their bending movements, closing tools hingedly mounted on the bed for engaging the said bent end portions of the wire, means for connecting the end portions of the wire to form a garment hanger, and means for stripping the finished hanger from the former.

8. In a machine for forming wire garment hangers, means for feeding wire from a reel, a fixed and movable guide bar between which the wire is fed, said movable bar having a wire receiving groove formed in the length thereof, a lowering tool positioned to engage the wire and move it from the guide bars to a lower level, means for moving one of the guide bars to free the wire and permit of the operation of the lowering means, means for forming a hook upon one end of the wire, means for bending the wire to form the body of a garment hanger, means for bringing the end portions of the wire together and means for twisting said end portions to complete the hanger.

9. In a wire forming machine of the class described, means for feeding wire into the machine, guide means to receive the wire, means for cutting the wire to lengths, means for transferring the wire from the guide means to hook forming means, means for forming a hook upon one end of the wire, a former around which the garment hanger is formed, tools for bending the two end portions of the wire around shoulder portions of the former, means to guide the end portions of the wire during said bending operations, closing tools for engaging the said

bent end portions of the wire and aligning them against the front of the former and means for securing the ends of the wires together.

10. In a wire garment hanger forming machine, means for feeding wire from a reel into the machine, means for cutting the wire off to form blanks, means for forming a hook upon one end of the wire blank, an elongated former having shoulder portions and a front projected nose portion, a combined wire guiding and stripping tool adapted to operate adjacent the nose of the former to guide the wire ends in position thereon, means for operating said tool to disengage it from said wire ends and to strip the completed hanger from the former.

11. In a garment hanger forming machine, means for feeding wire from a reel into the machine, means for cutting the wire into lengths on one level, means for shifting the wire blank 20 to another level, means for forming a hook upon the wire blank while in said second level, means for moving the wire blank to a third level, a former, means for bending the wires around said former while in said third level, means for securing the end portions of the wire together.

12. In a garment hanger forming machine adapted to handle three separate wires during a cycle of the machine, including means for feeding and cutting off wire to produce a wire blank, 30 mechanism for forming a hook upon another blank, and wire bending means and twisting tools upon a third blank, the three said sets of operations being performed simultaneously upon the three blanks in a manner to produce a complete hanger with each series of operations, said operations being performed on different levels one below the other.

13. In a garment hanger forming machine, means for feeding wire into the machine, a former around which the hanger is formed, a pair of swinging arms carrying closing jaws to bend and shape the wire against the former, means for swinging the arms forward and backward in their bending operations, means for also 45 lowering and raising the arms and jaws horizontally with each swinging movement of the arms to carry the wire ends from one level to another and means for securing the ends of the wires together after being bent to position.

14. In a wire forming machine of the class described, means for feeding wire from a reel, guide bars between which the wire is fed, means for cutting the wire off to form blanks, means for operating the guide bars to free the blanks after 55 the same have been cut, means for forming a hook upon one end of the blank, means for bending the wire to a form, a twisting head, means for reciprocating the same to engage and disengage the wire ends and means for rotating the head 60 to twist the end portions of the wire.

15. A wire forming machine of the class de-

scribed, including a bed, means for feeding wire into the machine, a former mounted on the bed and having a small extended nose portion, arms carrying tool to bend the wire around the former and dispose them across the nose, a movable tool 5 having a V-shaped notch in its front edge to receive and direct the wire end portions and align them against the nose, means for withdrawing the tool from the wires, to position them against the nose, and means for twisting the end portions 10 of the wire together.

16. A wire forming machine of the class described, including a bed and instrumentalities disposed to operate upon wires while in approximately horizontal planes and on three different 15 levels above the bed, and comprising first, feeding and cutting mechanisms, second, hook forming means and third, bending and twisting means, the mechanisms being so arranged and timed as to simultaneously perform different 20 operations upon the three wires.

17. The combination with a wire forming machine, of a wire feed mechanism comprising a drive shaft two pairs of wire feed rollers adapted to draw wire from a roll and feed it into the machine preparatory to cutting the wire, a relatively large gear driven from the drive shaft and carrying a series of rollers, an associate gear having a like number of radial slots, an intermediate shaft and reducing gearing between the 25 last mentioned gear and the feed rollers for operating the same, the said rollers of the one gear and number and position of the slots carried by the driven gear being such as to cause successive 30 engagements of the rollers with the slots and to produce a slight dwell of the driving gear and stoppage of the feed rollers between said engagements and a resultant slight stoppage of the 35 feeding of the wire.

18. The combination with a wire forming machine, of a wire feed mechanism comprising a drive shaft, two pairs of wire feed rollers adapted to draw wire from a roll and feed it into the machine preparatory to cutting the wire, a relatively large gear driven from the drive shaft and carrying a series of rollers on one side, an associate gear mounted on a different shaft having a like number of radial slots formed in its side 40 next adjacent the rollers, an intermediate shaft and reducing gearing between the last mentioned 45 gear and the feed rollers for operating the same, the said rollers of the driving gear and number and position of the slots carried by the driven gear being such as to cause successive engagements of the rollers with the slots and to produce a slight dwell of the driven gear and stoppage of the feed rollers between said engagements and a resultant slight stoppage of the feeding of the 50 wire.
